Application July 10, 1936, Serial No. 89,862

3 Claims. (Cl. 122—135)

The present invention relates to improvements in boilers, furnaces or the like, and its main object is to provide an improved construction and arrangement of parts in a boiler, whereby, the water in the cells circulates in one direction while the fumes and smoke circulate in an opposed direction.

Another object is to provide an enlarged heating surface and generally produce a boiler of this character which is efficient, cheap to operate, durable, readily accessible for cleaning and repair purposes.

The invention broadly consists in providing one or more series of parallel (horizontal and vertical) water cells having intermediate corresponding and adjoining fume flues, said cells being readily removable if repairs are necessary. The cells are preferably externally formed by means of an outer tubular wall on the inner side of which the cells are formed and radially disposed, each of said water circulating cells being provided on the inner side with sheet of dented or corrugated metal, each of said dents being conveniently distanced from one another; said outer casing and dented sheet being closed at both ends and welded or otherwise staunchly secured together, thereby, providing a water column having upon its inner wall a plurality of radial parallel and longitudinal fins, and corresponding recesses, which, when closed by the tubular wall of the adjacent cell, will provide a plurality of longitudinal radially formed flues for the fumes and gases to pass therethrough. The outer cell unit is of relatively larger diameter than the adjacent inner cell, in order that said cells may fit in one another, as further fully described.

In the accompanying drawings:—

Fig. 1 is a side elevation view of the combination of a horizontal and an upright boiler, operatively connected together;

Fig. 2 is an enlarged cross section view on line 2—2 of Figures 1 and 3;

Fig. 3 is an enlarged longitudinal section view on line 3—3 in Figure 2;

Fig. 4 is an enlarged cross section view on line 4—4 on Figure 1;

Fig. 5 is a vertical section view on line 5—5 in Figure 4;

Fig. 6 is a vertical segmentary section view on line 6—6 of Figure 3.

Like numerals of reference indicate corresponding parts in each figure.

Referring to the drawings and particularly to Figure 1, 10 indicates one of the elongated tubular cell-units of a boiler, said unit being preferably

shown in horizontal position and closed at one end by the smoke collecting box 11, and the fire and ash doors 11a and 12 respectively, and at the other end by the cleaning door 13 and end wall 13a. The upright elongated tubular cell-unit 14, disposed adjacent said unit 10, preferably reposes upon a cement base and is closed at its uppermost end by the top member that is formed of a plurality of cells 16. Over and above said unit 10 is located the fuel feeding hopper 17, 10 and 18 is a smoke-pipe connecting the unit 10 to the unit 14, while 19 is the smoke-pipe leading to the chimney.

The horizontal cell-unit 10 which is fully disclosed in Figures 2 and 3 of the drawings, consists of an outer tubular shape wall 20 and a longitudinally dented or corrugated cylindrical inner wall 21, distanced parallel and longitudinal thereto and suitably joined together at each end by welding or any other convenient means, one end 20 of which is bent to form a rear upright wall 13a, whereby is formed an outer water circulating cell 23. Adjacent one end of said cell is located the water-inlet opening 24, and 25 is the water-outlet which is preferably connected by means of the pipe 26 to the water-header 27 disclosed in Figure 1.

Adjacent and resting against the ridges of the corrugations of the wall 21 is provided an intermediate water-circulating cell 28 which also forms 30 the combustion chamber and which consists of a tubular shape wall 28a of smaller diameter than the wall 21, and another parallel and suitably distanced wall 30, both of which are joined together at their ends by welding or any other 35 suitable means, one end of which is bent to form an intermediate upright deflecting wall 29 which is preferably distanced from the wall 13a. The said intermediate cell 28 which is longer in front than the outer cell 23 preferably extends outwardly through the end of said outer cell and in its upright wall 29 is provided an opening 31 connected by means of a pipe 31a, which registers with an opening 31b, provided in the outer upright cell wall 13a. Water is supplied to said intermediate cell 28 by means of the water pipe 33, 40 which is connected to said pipe 31a and 34 is the water outlet opening which is suitably connected to the water header 27, by means of the pipe 35.

Located in the front end of the cells 23 and 28 is the fume or smoke collecting chamber 36, which is formed by the casing 11, upon which the fire and ash doors 11a and 12 are respectively mounted.

Upon the inner wall of the cell unit 28, may be provided, if it is desired to further increase the heating surface, a dented or corrugated metal semi-circular sheet 37. This dented metal sheet 5 is preferably located around the upper portion of the walls of the fire-box located in the cell 28, but it should be understood that it is only an addition which may be dispensed with. If used, the wall 30 of the cell 28 only extends mid-way 10 and the tubular wall is completed by said dented metal sheet 37. To strengthen the said sheet 37, two or more metal straps 39 are provided, upon which said sheet is welded. It is also desirable, to prevent said cell from collapsing, to also provide 15 strengthening spacing members 40 which engage said straps 39 and the wall 28a. The fuel hopper 17 engages into a suitable passageway 41 respectively provided in the upper walls of the cell units 23 and 28, said hopper extending into 20 the fire-box in cell 28 in the shape of an elongated rectangular member 42 but terminating at a suitable distance from the grate 43. The dented sheet 37 extends downwardly and parallelly to the walls of the said member 42, to its open lower end 25 to which it is joined by welding or any other means, thus providing around said member 42 a protective water circulating cell 28 thus preventing said extension member from overheating. The open lower-end of said member 42 is preferably closed by any suitable means, such as a 30 sliding closing plate 45, which may be operated by a rod (not shown) projecting outside the firebox or by any other convenient manual or mechanical means.

The grate 43 may be of any suitable type, but, in the present instance it is shown with a water-circulation therethrough. It principally consists of a plurality of longitudinal parallel and suitably distanced tubular bars 46, extending from 40 a two-way header 47, preferably located in the forward end of the cell 28, said header being connected to the cell 28 by means of the connections 47a and 47b respectively, whereby a water circulation will be provided. The tubular bars 46 are respectively connected to one side of said header extending at right angle therefrom to adjacent the upright wall 29 and then bent at right angle, as at 48, and return to be connected to the other side of said header. 45

In the outer cell unit 23, the cold water enters 50 through the inlet 24, flowing in the direction of the arrows 49, passing through the outlet 25 into the pipe 26 and then into the header 27. The heated fumes and smoke follow the direction shown by the arrows 50, which is inverse to that 55 of the water circulation, then passing through the passage or space 51 formed by the upright ends 13a and 29 of the cell units 23 and 28, through the flues 52, formed by the dented wall 21 and wall 28a of said units, into the fume and smoke collecting chamber 36, through the smoke pipe 18. If the upright unit 14 is used in connection with the horizontal cell unit, said fumes enter the cell-unit 14 through a suitable inlet 60 opening which will be hereinafter disclosed. 65

The upright cell unit 14 is preferably used when it is necessary to enlarge the heating surface. It consists of a tubular upright outer tubular wall 53 having adjacent its lower end, in 70 one side thereof, the smoke inlet 54, to which is connected the smoke-pipe 18, leading from the cell unit 10, and the smoke outlet 55 in the opposite side of the wall, to which connects the smoke pipe 19, leading to the chimney. An inner wall 75 56, similarly dented to that of the cell 23 (unit

10) is suitably distanced and is parallel to said wall 53, the end of said walls being preferably welded to form a circular cell 57, and the outer side of the said corrugated wall 56 forming a plurality of vertical parallel and radially disposed flues 58, which are laterally partly closed by the adjoining semicircular members 58a within which the adjacent cell unit 59 is located. The said cell 59 is composed of the dented walls 60 and 61 respectively. The walls 60 and 61 are 10 preferably spaced from one another, their ends being preferably closed diagonally (see Figure 5) and welded together to form a water circulating cell. The dented wall 61 is also held in fixed position by means of the inner tubular member 63, said tubular member being closed at both ends to form a central water cell 63a. Intermediate of said cells 57 and 59 are formed 15 a plurality of vertical and parallel fume-flues 64 and centrally of said cell 63a are provided 20 four additional fume-flues 65.

All of said cells 57, 59 and 63a are closed at their ends by means of welding or in any other suitable manner and each is respectively connected to the outlet opening 66, by means of 25 the angular pipes or connections 67 and 68 respectively. The cell 57 preferably extends upwards to connect directly with the outlet 66, and the connections 67 and 68 are respectively connected thereto. A pipe 69 connects said outlet 30 66 to the header 27. The water enters through a suitable inlet opening 70 by means of the pipe 71 (see Figure 1) into the cell 57, through another water inlet opening (not shown) and into the intermediate cell 59, after which it passes 35 through another water inlet (not shown) through the inlet into the inner or central cell 63a. The heated fumes enter through the fume inlet 54 into the lower chamber 73 which is divided into two sections, by means of the partition wall 74, to form another chamber 75, so as 40 to divide the fume-flues into two separate units, one unit being used for circulating the fumes upward through the flues 58, 64 and 65, which then enter into the upper chamber 76, from 45 which they pass through the second unit downward into the lower chamber 75, through the outlet 55 and the pipe 19.

The partition wall 74 is preferably water-jacketed and consists of two walls 77 and 78, 50 distanced from one another the upturned end 78, which is closed, abutting against the lower closed end of the cells 59 and 63a, while the other end is connected at 79 to the lower end of the cell 57.

The arrows 49 indicate the source of the water circulation, while the arrows 50 disclose that 55 of the heated fumes.

The several cell units are readily dismounted for cleaning or repair purposes. By removing 60 the fume collector 11, located at the forward end of the horizontal unit, access is readily had to the flues if it is desired to clean them. Should it be necessary to repair the cells, the connections of the outlet and inlet pipes are unconnected and the inner unit (unit 10) 28 may be easily pulled-out to expose the unit 23. In the upright unit 14, the cover or closure 16 is lifted and the connections securing the tubular members 67 and 68 are disconnected, thus allowing 70 for readily removing the inner cell units, after the other connections have been disconnected.

It should be understood that only one preferred form of the present invention is herein disclosed and that modifications thereto may be made 75

without departing from the spirit and scope of the following claims for novelty.

What I claim as my invention is:—

- 5 1. The combination of a horizontal and an upright boiler consisting of a plurality of horizontal water-circulating cell-units of different diameters and disposed within one another, one of said units having a plurality of radially disposed longitudinal and parallel fin-like members and corresponding intermediate recesses, the adjoining cell wall of the adjacent inner cell laterally closing said recesses to form a plurality of fume flues and a fire box within the inner cell unit, the inner cell unit having a longitudinally corrugated top wall 5 above the fire box to increase heat capacity of the boiler or furnace, metal straps extending across the outer sides of said corrugated top wall and welded thereto, brace members between said straps and the outer adjacent cell unit, and a fuel 10 hopper having a discharge neck extending laterally through the cell units and surrounded by the water passages of the cell units.
- 10 2. In a boiler or furnace of the character described, a plurality of upright water circulating cell units of different diameters and disposed within one another, said units having a plurality of radially disposed longitudinal and parallel fin like members and corresponding intermediate recesses, an adjoining wall laterally closing said recesses to form a plurality of fume flues, a fume collecting chamber located below said cell units and a fume collecting chamber located above said cell units, and fume connecting means between horizontal and the upright cell units, substantially 15 as described.
- 15 3. In a boiler or furnace of the character described, a plurality of horizontal water-circulating cell units of different diameter and disposed within one another, one of said cell units having a plurality of radially disposed longitudinal and parallel hollow fin-like members and corresponding intermediate recesses, an adjoining wall laterally closing said recesses to form a plurality of fume flues, a fume collecting chamber located below said cell units, a fume collecting chamber located above said cell units, a transverse partition in the lower fume collecting chamber dividing the same 20 into a fume receiving section for directing the fumes upwardly through a section of the cell units to the upper fume collecting chamber with the other section of the lower fume collecting chamber leading to an outlet. 25
- 20 4. In a boiler or furnace of the character described, a plurality of horizontal water-circulating cell units of different diameter and disposed within one another, one of said cell units having a plurality of radially disposed longitudinal and parallel hollow fin-like members and correspond- 30

JOSEPH EDMOND THIBAUDEAU.
